UNITED STATES PATENT OFFICE.

KASPAR I. DIETHELM, OF NEW YORK, N. Y.

WIRE FABRIC.

1,385,434.

Specification of Letters Patent. Patented July 26, 1921.

Application filed December 22, 1917. Serial No. 208,407.

To all whom it may concern:

Be it known that I, KASPAR I. DIETHELM, a citizen of Switzerland, residing at New York city, in the county of Bronx and State 5 of New York, have invented certain new and useful Improvements in Wire Fabrics, of which the following is a specification, reference being had therein to the accompanying drawing.

10 My invention relates to improvements in screens or wire-mesh products, and is more particularly intended and adapted for use in connection with screens adapted to be rolled upon a shaft or spindle such as a 15 shade roller.

In Figure 1 I have illustrated in plan view a section of screen or fabric embodying an application of my invention. Fig. 2 is 20 a similar view illustrating modifications, and Fig. 3 is another similar view illustrating other modifications.

In the form of screen illustrated in Fig. 1 the wire 4 crosses the wire 5 and loops with the wire 6 at 7, as shown, again crossing the 25 wire 5 twice and again looping with the wire 6 as shown, while the wire 5 loops with the wire 15 as indicated at the intermediate point 8 as shown, each pair of wires such as 4-5 forming a substantially straight line 30 of diamond-shaped figures; whereas in Figs.

2 and 3 a pair of zigzagged strands are looped at their adjacent corners and another pair are interlaced between the first pair and also looped at their adjacent corners, crossing the first pair at right angles 35 about midway between corners, while another pair of zigzagged strands are looped between the loops of the first pair. In Fig. 2 the wire 9 continues the length of four 40 squares, as shown, looping with the wire 10 at 11; and in Fig. 3 the wire 12 extends for only three squares, as shown, looping with the wire 13 at 14 as indicated. In other words, in Fig. 3, a pair of zigzag wires

45 12-13 are looped at their adjacent corners, another pair 16-17 interlock with the first pair, and a third pair 18-19 interlock with the first two pairs, all strands being straight

except at the corners. From the foregoing it will be seen that the most flexible form is 50 shown in Fig. 1, each length of wire covering only two squares, whereas in Fig. 3 it covers three squares, and in Fig. 2 it covers four squares. In each instance, however, there is rigidity imparted to the screen 55 where each wire crosses the other, the flexibility or pivotal point only being at the line along which the loops are formed, thus facilitating the rolling of the screen upon the rod or roller, the form shown in Fig. 1 being 60 best adapted for a roller of less diameter.

In the use of a screen of this fabrication it has been found that there is less tendency for the several sections to crinkle up or overlap, and the fabric has been found to 65 possess better rigidity and stiffening and to retain its uniformity of appearance to better advantage while at the same time being strong and durable and particularly well adapted for roller screens such as may be 70 applied to windows for keeping out flies or mosquitoes, and for fire screens, concrete reinforcement, etc.

Of course it will be understood that various modifications may be made in the construction and arrangement of parts without departing from the spirit of the invention as claimed.

I claim:

In a fabric of the class described, a pair 80 of zigzag strands looped at their adjacent corners, another pair of zigzag strands interlocked with said first pair and also looped at their adjacent corners and crossing said first pair substantially at right angles and 85 between said corners, and a third pair of zigzag strands interlocked with said first two pairs, all of said strands being straight except at said corners.

In testimony whereof I hereunto affix my 90 signature in the presence of two witnesses.

KASPAR I. DIETHELM.

Witnesses:

ETHEL GARDNER,
DAVID H. DOUGLASS
